CLAIM

The ornamental design for a combined desk set and holder therefor, as shown and described.

DESCRIPTION

FIG. 1 is a right front perspective view of a combined desk set and holder therefor showing my new design;
FIG. 2 is a top plan view thereof;
FIG. 3 is a front elevational view thereof;
FIG. 4 is a side elevational view, the opposite side being a mirror image thereof;
FIG. 5 is a bottom plan view thereof;
FIG. 6 is a rear elevational view thereof;
FIG. 7 is a side elevational view in an exploded condition drawn to a reduced scale, the opposite side being a mirror image thereof; and
FIG. 8 is a bottom plan view thereof in an exploded condition drawn to a reduced scale.

FIG._1

FIG._4

FIG. 2

FIG. 5

FIG. 3

FIG. 6
